COMB

Helen Evans, Brooklyn, N. Y.

Application May 20, 1940, Serial No. 336,258

5 Claims. (Cl. 132—16)

The invention relates to a hair waving implement and more especially to a hair wave-forming comb.

The primary object of the invention is the provision of an implement of this character wherein the same through self-adjusting teeth involved in a comb construction will enable the latter to conform to the shape of the head of a person so that the strands of hair upon the head can be worked upon for imparting a wave or waves thereto throughout a determined area of the head and in this manner through the wide range of the implement the hair can be curled with dispatch or waved in the least possible time.

Another object of the invention is the provision of an implement of this character wherein the teeth are sustained under tension individually and in this manner being self-adjustable to assure contact with the scalp irrespective of irregularity in the head formation so that complete waving or curling of the hair can be carried forth with ease and rapidity, the implement being novel in its entirety.

A further object of the invention is the provision of an implement of this character wherein in the use thereof a holding element can be brought into position so that the strands of hair can be held firmly during the curling or waving thereof without the necessity of the use of the fingers on the hand of a person or operator, leaving the hand or hands free for manipulation of the implement in carrying forth the curling or waving operation.

A still further object of the invention is the provision of an implement of this character wherein on the breaking of any of the teeth thereof, new teeth can be placed therein or if the teeth become defective in operation, repairs can be made with ease and dispatch.

A still further object of the invention is the provision of an implement of this character, which is simple in its construction, thoroughly reliable and efficient in operation, readily and easily handled for the curling or waving of hair upon the head of a person, being self-adjustable, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a side elevation partly in section of the implement constructed in accordance with the invention.

Figure 2 is a top edge view partly in section of the implement.

Figure 3 is a sectional view taken approximately on the line 3—3 of Figure 1 looking in the direction of the arrows.

Figure 4 is a perspective view of one of the teeth of the implement detached therefrom.

Figure 5 is a side elevation of the holding element for the hair.

Figure 6 is a sectional view taken on the line 6—6 of Figure 5 looking in the direction of the arrows.

Similar reference characters indicate corresponding parts throughout the several views in the drawing.

Referring to the drawing in detail, A designates generally the combing implement constituting the present invention while B denotes generally the holder for the strands of hair upon the head of a person usable with the implement A and such implement and holder will be hereinafter fully described in detail.

The implement A, which is in the nature of a comb, comprises an outwardly arched, hollow body 10, which is really the main blade creating a back to a comb. This body 10 has a removable side cover plate 11, which is separably fastened in place by fasteners 12. The body 10 is outwardly arched in one direction so that in its application it will substantially conform to the contour of the scalp or head of a person.

Formed interiorly of the body 10 are spaced, parallel guideways 13, which through restricted openings 14 through the convexed edge 15 of said body 10 expose or project a plurality of combing teeth 16 beyond said convexed edge 15 of the body for a purpose presently described.

Each tooth 16 is formed with a head 17 conforming to the guideways 13 which are substantially squared in cross section. These heads 17 slidably fit within the guideways 13 for self-adjustment individually of the teeth 16 in the use of the implement.

The teeth 16 are of uniform length with respect to each other so that in the projecting thereof from the body 10 such teeth at the free tip ends thereof follow the concaved edge 15 in conformation similar thereto.

Confined within the guideways 13 and active upon the heads 17 of the teeth 16 are coiled compression springs 18 which urge the said teeth 16 outwardly through the restricted openings 14 and

beyond the concaved edge 15 and at the same time enable self-adjustment individually of the said teeth and the maintenance of the same under tension. The implement in its construction, when 5 in use, will enable the teeth 16 to become adjusted in conformity with the shape of the head of a person and assures the contact of these teeth with the scalp of the head and also enables the strands of hair upon the head to be worked for 10 the curling and waving thereof through manipulation of the said implement.

Adapted to be used in connection with the implement A is the holder B, which comprises an arched gripping member 19, made preferably 15 from rubber, and from which intermediate the ends thereof protrudes a hand grip or grasp wing 20, which is also of the same material as the arched gripping member 19. This holder B is designed to saddle the head of a person so that 20 the strands of hair when to be worked upon by the implement A can be held against the scalp, the said holder B being grasped in the hand of an operator at the wing 20 and brought into saddling position to have the member 19 overlie 25 the hair upon the head so that when such holder B is pressed against the latter the strands of hair will be permanently held thus relieving the necessity of holding these strands by the fingers of a hand as is customary. The implement A is 30 manipulated similarly to a standard make of comb so that the curling of the hair or the waving thereof can be brought about concurrently when using the holder B for the purposes specified. The teeth 16 of the implement A will become adjusted 35 individually through the self-adjustment thereof and in this manner the combing of the hair can be had with dispatch and ease and without excessive manipulation of a comb of standard make as is generally used for the waving or curling of the hair. The implement A is of wide range so 40 that maximum extent of strands of hair can be worked in one movement of the implement for the curling or waving of such hair.

What is claimed is:

1 An implement of the kind described comprising 45 an arched body forming a comb back and

having a plurality of guideways therein, comb teeth slidably fitted in said guideways, and tensioning means active upon the teeth for individual self-adjustment thereof under tension.

2. An implement of the kind described comprising 5 an arched body forming a comb back and having a plurality of guideways therein, comb teeth slidably fitted in said guideways, tensioning means active upon the teeth for individual self-adjustment thereof under tension, and heads 10 formed on the teeth and shaped to the guideways for preventing rotation of said teeth under self-adjustment thereof.

3. An implement of the kind described comprising 15 an arched body forming a comb back and having a plurality of guideways therein, comb teeth slidably fitted in said guideways, tensioning means active upon the teeth for individual self-adjustment thereof under tension, heads 20 formed on the teeth and shaped to the guideways for preventing rotation of said teeth under self-adjustment thereof, and a cover piece on said body for giving access to the guideways.

4. An implement of the kind described, comprising 25 a body forming a comb back having a plurality of guideways therein provided with restricted openings at their lower ends, comb teeth sliding in said openings and having heads 30 slidable in said guideways, and coil springs in said guideways engaging the heads of the comb teeth for normally holding the heads in the lower ends of the guideways.

5. An implement of the kind described, comprising 35 a body forming a comb back and having a plurality of guideways in one side thereof with restricted openings at their lower ends communicating with the lower edge of the back, comb teeth sliding in said openings and having heads 40 slidable in said guideways, coil springs in said guideways engaging the heads of the comb teeth for normally holding the heads in the lower ends of the guideways, and a cover plate closing the guideways and retaining the springs and the comb teeth in said guideways.

HELEN EVANS. 45
